HARRY BREWER AND NOAH G. BREWER, OF SIDNEY, NEBRASKA.

OIL-BURNER.

1,252,228.

Specification of Letters Patent. Patented Jan. 1, 1918.

Application filed June 26, 1917. Serial No. 177,090.

To all whom it may concern:

Be it known that we, HARRY BREWER and NOAH G. BREWER, citizens of the United States, residing at Sidney, in the county of Cheyenne and State of Nebraska, have invented new and useful Improvements in Oil-Burners, of which the following is a specification.

This invention relates to liquid fuel burners, and more especially to those employing an overlying retort; and the object of the same is to produce a burner for gasoline, kerosene, or crude oil which is capable of being placed entirely within a fuel box excepting its nozzle, the latter standing outside the fire door and opposite an opening therein.

Coacting with the burner of the specific type hereinafter described is a coarse granular material placed within said fire box so as to break up the flame issuing from the nozzle. Within the retort is fine granular material which serves as a filter for the oil. The use of these materials may be said to be one of the features of the present invention.

The preferred construction of our burner is set forth in the following specification and shown in the accompanying drawings wherein:

Figure 1 is a general side elevation partly broken away, or in effect a diagram of this complete invention as applied to a fire box, the latter being shown in section.

Fig. 2 is a slightly different arrangement of the oil tank, showing the use of compressed air admitted thereto to cause the flow of the oil.

We do not wish to claim specifically the fire box nor the door thereto, but as a part of this invention we make use of a metal casing which we will call a box 1 whose front may be closed by a door 2 having an opening 3. This box may well be the fire box of an ordinary stove, or that of a furnace if the device is of large size. The oil flows from a tank 4 through a feed pipe 5 and control valve 6 to a retort 7 which latter is a pipe of ample size disposed within and preferably extending horizontally through the box 1 near the upper portion thereof; and in the retort within said box we form an arch 8 which normally rises from the plane of the remainder of the pipe 7 as seen in Fig. 1. The inlet end of the retort is

connected by a coupling 9 with the feed pipe 5, and the outlet end of the retort is connected by an elbow 10 with the casing of a needle valve 11 having a wheel 12 on its valve stem at the outer end and a nozzle 13 at its inner end directed axially toward the opening 3 in the door 2. By preference said opening is of about two inches in diameter, and the tip of the nozzle is disposed about two inches away from the plane of the door, but these measurements may be varied when the device is made in extra large or extra small sizes.

Within the retort pipe throughout its length is fine granular material 15, such as gravel, and the same serves as a filter for the liquid fuel. It will be obvious that by turning the retort on its axis the arch 8 may be caused to stand horizontal, and may be caused to depend from the remaining portion of the retort pipe if it were not for the coarse granular material 16 with which the lower portion of the box 1 is filled. This coarse material we preferably make in the form of cubes or bricks, and it is quite possible to use ordinary builders' bricks 80 promiscuously piled within the box 1 as shown in Fig. 1. The function of these coarser grains or bricks is to break up the flame, which latter burns at the tip of the nozzle 13 where sufficient oxygen is received to 85 maintain combustion. The coarse granular material or bricks 16 become highly heated, and preserve the heat of the entire structure even after the supply of oil is cut down to a minimum or perhaps cut 90 off entirely. From time to time the retort pipe is rotated, as the coupling 9 will permit. It is obvious that the fine granular material 15 would slip or fall away from the top of the arch 8 and slide down the 95 arms of the same, thus leaving a space at the top of the arch where the pipe contained nothing to take up the excessive heat to which it was subjected. Therefore if the retort be turned on its side, first one way and 100 then the other, and perhaps even to points at either side a little below the horizontal, the result would be that the granular material 15 would be dislodged from its packed condition in the angles between the arch 105 and the straight portions of the retort pipe, and to an extent re-distributed throughout the length of the arch. At long intervals

the entire retort pipe will be removed and the packing withdrawn and replaced by other fine granular material. The proportions and materials of parts are not essential.

In Fig. 2 is shown a tank 4' from which the oil does not flow by gravity as seen in Fig. 1. In order to cause it to flow, this tank is connected at 4" with a source of compressed air, and therefore the tank could be in the cellar.

What is claimed as new is:—

1. In a liquid fuel burner, the combination with a box having a door in one end provided with an opening, and coarse granular material within the lower portion of said box; of a retort pipe having straight ends mounted through the ends of said box and an interposed arch overlying said coarse granular material, fine granular material within said retort pipe and its arch, means for supplying liquid fuel to one end of the pipe, and a valved nozzle connected with

the other end of the pipe and directed toward said opening.

2. In a liquid fuel burner, the combination with a box having a door in one end provided with an opening, and coarse granular material within the lower portion of said box; of a retort pipe passing transversely through the ends of said box above its coarse granular material and containing within the box an upstanding arch, the pipe containing fine granular material, a liquid tank and supply pipe, a coupling connecting such pipe with the inlet end of the retort, a control valve in said inlet end, an elbow on the outer end of the retort pipe, and a valved nozzle carried by said elbow and directed toward the opening in the box-door, the whole for use substantially as described.

In testimony whereof we affix our signatures.

HARRY BREWER.
NOAH G. BREWER.
